TOTALIZER CONTROL MECHANISM FOR
MULTIPLE TOTALIZER ADDING-SUB-
TRACTING MACHINESHarry L. Lambert, Webster, N. Y., assignor to The
National Cash Register Company, Dayton,
Ohio, a corporation of Maryland

Application May 27, 1949, Serial No. 95,703

3 Claims. (Cl. 235—60.31)

1

This invention relates to improvements in adding-subtracting machines and is particularly drawn to an arrangement for increasing the number of totalizers in such machines without a corresponding increase in size of the machine and without completely redesigning the machine.

It is an object of this invention to provide an adding-subtracting machine, which was originally built to contain one totalizer, with three totalizers without appreciably increasing its size and with a minimum of change to the mechanisms making up the machine.

A further object of the invention is to provide a novel totalizer selecting means which can select any one of a plurality of totalizers for operation and at the same time will non-add the remaining totalizers.

A further object of the invention is to provide novel means for operating a totalizer engaging means in total and sub-total taking operations.

Another object of the invention is to provide a compact totalizer arrangement in which two independently operable totalizers can be provided in a space which is substantially the same as that previously required for one totalizer.

Another object of the invention is to provide a compact dual totalizer arrangement in which a second totalizer is mounted in tandem with a first totalizer and within but independently of the supporting frame for the first totalizer.

Another object of the invention is to provide a novel control for tens transfer mechanism whereby either of two totalizers can control a single transfer mechanism to make necessary tens transfer entries in either totalizer in adding and subtracting operations.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In the drawings:

Fig. 1 is a vertical section through the machine, showing the mechanism associated with, and controlled by one denominational row of keys on the keyboard.

Fig. 2 is an exploded perspective view of a portion of two adjacent totalizers and their related tens transfer mechanism, showing how either of the totalizers can control the tens transfer mechanism.

Fig. 3 is a side elevation view of the right side of the machine.

2

Fig. 4 is a vertical section of the machine, taken just inside the right side frame.

Fig. 5 is a perspective of a portion of two adjacent totalizers and their supporting frames.

Fig. 6 is a side elevation view of the left side of the machine.

Fig. 7 is a detail view of a portion of the totalizer engaging means for the #1 totalizer and the totalizer selecting means for controlling this engaging means in the selection of the totalizers for operation.

Fig. 8 is a detail view of the engaging means for the #2 totalizer and the totalizer selecting means for controlling this engaging means in the selection of the totalizers.

Fig. 9 is a detail view of the total and sub-total lever and its control over the engaging means for the #1 and #3 totalizers.

Fig. 10 is a detail view of the means for setting a symbol type bar under control of the totalizer selecting means to enable a record of the totalizer selection to be made.

Fig. 11 is a detail view of the engaging means for the #3 totalizer and the totalizer selecting means for controlling this engaging means in the selection of the totalizers.

Fig. 12 is a plan view of a section of the #2 totalizer engaging mechanism taken along the line 12—12 in Fig. 6.

Fig. 13 is a plan view of a section of the #3 totalizer engaging means taken along the line 13—13 in Fig. 3.

Fig. 14 is a plan view of a portion of the totalizer engaging means and totalizer selecting mechanism located at the right of the machine.

Fig. 15 is a view of the #1 and #2 totalizers, taken in the direction of the arrow 15 in Fig. 1, with portions of the totalizers omitted in order to show their supporting frames more clearly.

Fig. 16 is a detail view of means for controlling the engaging means for the #1 and #3 totalizers in a non-add operation.

The invention is shown embodied in an adding-subtracting machine of the type shown generally in the United States patents to Peters, Nos. 1,386,021 and 1,646,105, which issued, respectively, on August 2, 1921, and October 18, 1927, and in the United States patent to White, No. 1,854,875, which issued on April 19, 1932.

As shown in these patents, this type of machine originally was provided with but a single totalizer, which was located in the upper part of the machine substantially between the keyboard and the printing mechanism and which was differentially operated by a set of arcuate actuating racks. In order that these machines would be of

reasonably small size, the various mechanisms therein were very compactly arranged, and, as a consequence, only a very limited space was available for the provision of additional totalizers.

By extending the side frames of the machine downwardly a slight amount, sufficient space has been provided in which to place a second totalizer and actuating racks therefor in the lower part of the machine. However, due to the location of other mechanisms in the machine, such as the keyboard and the stop bars, and the printing mechanism, it is practically impossible to add further similar actuating racks and totalizers, without completely rearranging the various mechanisms of the machine.

In spite of these conditions, the novel arrangement can enable a further totalizer to be included in the machine without rearranging the various mechanisms of the machine. This has been accomplished by mounting a totalizer in front of the upper totalizer within the usual upper totalizer supporting frame. This further totalizer has its wheels located in tandem with and closely adjacent the wheels of corresponding denominations of the upper totalizer and is engageable with the same actuating racks as the upper totalizer but is mounted for rack-engaging movement independently thereof.

Suitable totalizer engaging means is provided for each totalizer to enable the totalizers to be operable individually for engagement with and disengagement from the actuating racks.

Novel totalizer-selecting means controls the several engaging means to coordinate the operation of the three totalizers and enable any one of the totalizers to receive entries in amount-entering operations, or to be operated in the usual non-add, total-taking, and sub-total-taking operations which can be performed by this type of machine.

In the following detailed description of the machine, the upper-rear totalizer will be considered the #1 totalizer, the upper-forward totalizer, which is mounted within the supporting frame for the #1 totalizer, will be considered the #2 totalizer, and the lower totalizer will be considered the #3 totalizer. The #1 totalizer and the #3 totalizer will be called main totalizers because they have similar operation, and the #2 totalizer will be called the extra totalizer. The #2 totalizer is termed the extra totalizer because its engaging action is different from the #1 and the #2 totalizer.

Novel means are provided whereby the #2 totalizer engaging means can be operated by the total lever to engage the totalizer with the racks at the beginning of a total- or sub-total-taking operation involving the #2 totalizer if not already in engagement therewith.

In order that required tens transfer entries can be made in the two upper totalizers, #1 and #2, the usual transfer levers have been modified so that they cooperate with both totalizers and are operated by the transfer cams on the particular one of the totalizers which is in engagement with the actuating racks and is receiving entries. This enables one transfer mechanism to serve both upper totalizers.

Inasmuch as the #1 and #2 totalizers are actuated by the same actuating racks it has been arranged that the #2 totalizer be disengaged from the actuating racks at the beginning of each machine operation, except in a total-taking or sub-total-taking operation, in the event that it has not been left disengaged at the end of the

last previous operation. This mechanism will be described later, in detail.

The manner in which the three totalizers are mounted in the machine and the means whereby the totalizers are selected for operation and are operated in various kinds of operations of the machine will be clear from the following detailed description.

DETAILED DESCRIPTION

In addition to the usual left and right side frames 50 and 51 (Figs. 1, 3, 6, and 15), the machine is provided with extension side frames 52 and 53 (Figs. 1, 3 and 6), which are secured, respectively, to the side frames 50 and 51 and extend downwardly therefrom.

The side frames 50 and 51 and the extension side frames 52 and 53, are retained in proper spaced relation by various cross bars and rods and serve to support the various mechanisms of the machine, as will be explained hereinafter when the various mechanisms are considered.

The machine is provided with the usual motor-operated driving mechanism, which is shown fully in United States Patent No. 2,423,084 which issued on September 30, 1947 on the application of H. L. Lambert. Since the driving mechanism, per se, forms no part of the novel construction, it will be but briefly described herein, and reference may be had to said Patent No. 2,423,084 for further details if they are desired.

A suitable electric motor 55 (Figs. 6 and 12), mounted on the side frame 50, operates, through a speed reduction gearing and a one-revolution clutch mechanism, to rotate a crank-arm 57. A link 58, which is pivotally connected to the crank-arm 57, is also pivotally connected by a pin 59 to an arm 60 loose on a rear shaft 61 and causes the arm 60 to be given a complete oscillation, first clockwise, then counter-clockwise (Fig. 6), for each rotation of the crank-arm 57. The arm 60 is connected to the rear drive shaft 61 by a yieldable driving connection which includes a lever 62 pivoted on the pin 59 and urged by a spring 63, connected between the arm 60 and the lever 62, to cause a roller 64 on the lever 62 to be maintained in a notch in a plate 65 secured to the rear shaft 61. The spring 63 is strong enough to maintain the roller 64 in the notch in plate 65 to thereby form a driving connection which will be operable to transmit the movement of the arm 60 to the shaft in normal operations but which will yield and allow the roller 64 to cam itself out of the notch in the plate 65 to interrupt the driving connection and allow the arm 60 to be driven independently of the shaft 61 if that shaft should be blocked against operation.

The shaft 61 extends transversely between the side frames 50 and 51 and is supported by suitable bearings for oscillating motion therein. Adjacent the side frame 51, the shaft 61 has secured thereto a plate-like member 70 (Figs. 3 and 13), which member is connected by a link 71 to the usual full-stroke sector 72, secured to a main shaft 73. The main shaft 73 also is mounted in the side frames 50 and 51 for oscillating motion therein at a point forward of the rear shaft 61.

The plate-like member 70 (Figs. 3 and 13) has, in its forward edge, a depression into which a roller 74, carried by a bellow crank 75, which is pivotally mounted on the side frame 51, is urged by a spring 76. The notch is so located in the member 70 that it will be opposite the roller 74

when the member is in its normal, home position, the cooperation of the notch and the roller 74 assisting parts of the machine to be restored to their normal, home positions.

A stub shaft 79 (Fig. 6), which is journaled in the lower part of the motor housing, has secured thereto an arm 80 for controlling the operation of the clutch and also has secured thereto another arm (not shown) for controlling the closing of a switch in the motor circuit. A spring 81, connected to the arm 80 and to a strap 82 connected to the side frame 50, urges the arm 80 and the shaft 79 counter-clockwise (Fig. 6), but this movement is prevented by a latching lever 83, only one end of which is shown in Fig. 3 but which is shown fully in said Patent No. 2,428,084. The latch is released by means including a link 84 (Fig. 3) which operates the latching lever 83 when the link is pulled forward by the clockwise movement (Fig. 3) of a trip lever 85. The trip lever 85 is pivoted on the side frame 51 and is urged counterclockwise (Fig. 3) by a spring 86 into its normal position, which is determined by a bent-over portion of the lever 85 engaging the side frame 51.

When the latching lever 83 is operated by the link 84 (Fig. 3), the shaft 79 (Fig. 6) and the arm 80 will be allowed to rock counter-clockwise (Fig. 6) to move a stud 87 on the arm 80 out of engagement with a clutch dog 88, forming a part of the clutch, thereby to allow the clutch to become effective to couple the motor to the crank-arm 57, and also will cause the motor switch controlling arm on the shaft 79 to close the motor switch and start operation of the motor.

Near the end of a machine cycle of operation, a cam member 89 on the crank-arm 57 will engage a roller 90 on the arm 80 and will restore the arm 80 and the shaft 79 clockwise (Fig. 3), against the action of the spring 81, to their normal positions, the latching lever 83 again becoming effective to retain them in these positions.

As the arm 80 and the shaft 79 are thus rocked clockwise, the arm 80 will move the stud 87 into engaging relation with the clutch dog 88 to render the clutch ineffective, and the motor switch controlling arm on the shaft 79 will open the motor circuit to stop the motor.

Pivotedly mounted on the trip lever 85 (Fig. 3) is a bell crank 95 which has an upwardly-extending arm 96 urged into engagement with an upwardly-extending arm of the trip lever 85 by a spring 97 with sufficient force that under normal operating conditions the rearwardly-extending arm of the bell crank operates as a rearward arm of the trip lever 85 and can be operated to rock the trip lever clockwise. A stud 98 on the bell crank can be engaged by a cam surface 99 on a subtraction control lever 100 or by a forward extension 101 (Fig. 4) of the usual non-add and total lever latch 102 pivoted on a stud 103 which extends from a side of the keyboard, to depress the free end of the rearwardly-extending arm of the bell crank 95 and rock the trip lever clockwise to initiate an operation of the machine in subtraction, total, sub-total, and non-add operations. A lever 105, which is mounted on the trip lever 85 on the same pivot as the bell crank, has thereon a stud 106, which lies over the rearwardly-extending arm of the bell crank and has another stud 107, which can be engaged by the usual motor bar to cause the rocking of the trip lever to initiate an operation of the machine to perform addition.

Keyboard

The machine is provided with a suitable keyboard upon which amounts may be set up to control the entries of amounts in the machine.

The keyboard used in the novel machine is of the well-known type fully shown and described in the United States patent to Schroder, No. 2,062,731, which issued on December 1, 1936, and to which reference may be had for the details of its construction.

For an understanding of the instant invention, it is only necessary to explain that the keyboard is made up of a plurality of denominational rows of digit keys 110, one row of which is shown in Fig. 1, which keys are normally out of controlling relation with the differential mechanism and which, when they are depressed to set up amounts to be entered into the machine, are moved into position to control the extents of movement of the differential mechanism according to these amounts. Each row of keys has associated therewith a plate 111, to which is connected a zero stop lever 112. The zero stop lever 112 normally is in position to block the operation of a differentially-operable means which is related to this row of keys but is moved from blocking position by a cam surface on the depressed key, which engages the plate 111 and shifts the plate to move the stop lever 112. A latching plate extends along each row of keys and cooperates with the keys of the related row to latch any key of the row in depressed position until another key of the row is depressed or until the keys in all the rows are released by the usual fingers on a key released bail 113 which shift the latching plates when the key release bail is rocked, the latching plate for the row of keys to the right of the row shown in Fig. 1 being shown at 114 in Fig. 1.

The keyboard is also provided with the usual locking bails 115, which are moved into cooperation with the keys of the rows by the movement of a slide 116 toward the right of the machine and cooperate with means on the keys to prevent the depression or release of the keys during an operation of the machine. The slide 116 is normally retained toward the left of the keyboard but is released for movement toward the right of the machine early in the operation of the machine in a manner fully disclosed in said Schroder patent.

Differential mechanism

The differential mechanism used in the novel machine is substantially like the one fully shown and described in the United States patent to White, No. 1,854,875, and will be but briefly described herein.

A differentially operable means is provided for each denominational row of keys 110, however, since all of the differentially operable means are substantially alike, it is believed that an understanding of the construction and operation of these means will be clear from a description of one of them.

As shown in Figure 1, a stop bar 120 is located immediately below the row of keys 110. This stop bar is pivotally connected at its rear end to a diverging lever 121 and is suitably guided by a supporting bar 122 at its forward end so as to be movable longitudinally immediately below the keys. A spring 123, which is connected to the stop bar 120 and to the supporting bar 122, normally urges the stop bar to the left. When the machine operates, the stop bar 120 will be

allowed to be moved to the left by the spring 123 until one of the abutments on the upper edge of the bar engages the lower end of a depressed key to limit the movement of the stop bar 120 to an extent which corresponds to the value of the depressed key.

The diverging lever 121 is pivotally mounted on a diverging lever shaft 124 and has a rearward extension to which is connected an amount printing type bar 125. As the stop bar 120 moves to the left, the diverging lever 121 will move therewith, and will rock counter-clockwise (Fig. 1) about the shaft 124 a distance proportional to the value of the depressed key, and will position the type bar 125 accordingly to place the type corresponding to the depressed key, in printing position.

Also pivotally mounted on the shaft 124, immediately adjacent the diverging lever 121, is a rack lever 126, which carries at its upper end a totalizer actuating rack 127, which rack is capable of actuating the #1 and #2 totalizers, as will be explained later herein.

The diverging lever 121 and its associated upwardly-extending rack lever 126 are provided with forwardly-extending, gooseneck-shaped arms which contain at their forward ends, slots 128 which are substantially radial to the shaft 124. A stud 129 carried by an arm 130 of a complementary lever, rotatable about a shaft 131, extends through the slots 128 in the forward extensions of the pair of levers 121 and 126, and couples these levers for joint movement during the operation of the machine for addition. Thus when the diverging lever 121 rocks counter-clockwise (Fig. 1) about the shaft 124 as the stop bar 120 moves forward to contact a depressed key, the upwardly-extending rack lever 126, which is coupled thereto by the stud 129, will be given a similar movement.

In order that the lower or #3 totalizer may be actuated under control of the keyboard, each upwardly-extending rack lever 126 has secured to the side thereof a downwardly-extending rack lever 132, which carries at its lower end a totalizer actuating rack 133.

The diverging lever 121, the rack levers 126 and 132, and the stop bar 120, are normally held in their home positions, shown in Fig. 1, by means of the usual cross-bar 134, which engages the front edge of the levers 121 and 126. The cross bar 134 extends across the machine and, as shown fully in said White patent, is supported at its ends by the usual pair of arms which are operated to move the bar forward an amount sufficient to allow the maximum extent of setting movement of these levers during the first half of a machine cycle, and which return the cross bar and the levers to the position shown in Fig. 1 during the last half of a machine cycle, as is well known in this type of machine.

In the operation of the differentially operable means, therefore, the diverging lever, the rack levers, and the stop bar will move with the cross bar 134 until one of the abutments on the stop bar 120 engages the lower end of a depressed key, to prevent their further movement, after which the cross bar 134 leaves the front edge of the levers 121 and 126 and continues its movement. In its return movement, the cross bar 134 picks up the diverging lever 121 and the rack lever 126 from their set positions and carries them, the downwardly-extending rack lever 132, and the stop bar with it back to their normal positions, as shown in Fig. 1.

Subtraction mechanism

Subtraction is performed in the instant machine by the well-known method of complementary addition.

In order to obtain the complement of the amount to be subtracted, mechanism similar to that shown in the White Patent No. 1,854,875 is used.

As explained earlier herein, the studs 129 on the arms 130 of the complementary levers on the shaft 131 couple the diverging levers 121 and the rack levers 126 for joint movement. This enables the rack levers 126 and the rack levers 132 to be displaced extents corresponding to the true value of the digits of an amount which is set up on the keyboard.

In subtracting operations, the shaft 131 is shifted towards the right of the machine, and the complementary levers, which are mounted on the shaft for rotation but not for axial movement thereon, will also be moved to the right. When the complementary levers are thus moved to the right, the studs 129 will move out of the slots 128 in the diverging levers 121 to uncouple the diverging levers from the rack levers 126. This lateral movement of the complementary levers will move arms 140 thereon into the path of movement of studs 141 carried by the stop bars 120.

A spring 142 connected between each diverging lever 121 and its related arm 140, urges the arm 140 into engagement with the stud 141 in subtracting operations. This spring is also effective, through the complementary lever and the stud 129, to urge the related rack lever 126 forwardly, so that the rack levers 126 and 132 can be set differentially when the cross bar 134 moves away from the rack levers 126 during the first part of a machine operation.

The stud 141 carried by the stop bar is so located thereon and in relation to its related arm 140 that, in orders above the units denominational order, when the arm 140 is moved by the spring 142 into engagement with the stud 141 in subtract operations, it will cause the rack levers 126 and 132 to be positioned an extent which will enable the "nines" complement of a digit set up in any of those denominations of the keyboard to be entered into the corresponding order of the totalizer.

The differentially operable means for the units denominational order operates in a similar manner, but the relation between the arm 140 on the complementary lever and the stud 141 carried by the stop bar is such as to cause the rack levers 126 and 132 to be positioned an extent which will enable the "tens" complement of the digit set up in this denomination of the keyboard to be entered into the totalizer.

It should be noted that, while the rack levers are operable to enter the "nines" complement, as required, of the digits making up amounts to be subtracted, as explained above, the diverging levers 121, which are connected to the stop bars 120, will be operated according to the true value of the various digits of the amount and will set the type bars 125 to print the digits which are set up on the keyboard.

The shaft 131 is shifted to the right in subtracting operations by means which are fully shown in said Patent No. 2,428,084, and which will be but briefly described herein.

The shaft 131 (Figs. 1, 3 and 6) has the usual lever 145 (Fig. 6) secured adjacent its left end,

which lever, at its lower end, carries a roller 146 extending into a cam slot in a plate 147 secured to the side frame 50. When the shaft 131 is rocked counter-clockwise as viewed in Fig. 6 or clockwise as viewed in Fig. 3, the roller 146, co-operating with the cam slot in the plate 147, will shift the shaft 131 to the right of the machine.

The means for rocking the shaft 131 to bring about its shifting movement are shown in Fig. 3. Secured to the shaft 131 is a lever having a forwardly-extending notched segment 148 and a downwardly-extending restoring arm 149. Loose on the shaft 131, adjacent the lever having the forwardly-extending notched segment, is another lever having one arm 150, to which a pawl 151 is pivoted, and having another arm 152, which carries a roller 153. A lever 155, pivoted on a stud 156 on the side frame 51, has a cam edge 157, which cooperates with the roller 153 and has a roller 158, which cooperates with a cam surface 72. When the sector 72 is rocked counter-clockwise during the first half of a machine cycle, the cam surface thereon cooperates with the roller 158 on the lever 155 early in the operation of the sector and rocks the lever 155 clockwise. As the lever 155 is rocked by the sector, the cam edge 157 on the fore part of the lever 155 acts on the roller 153 to rock the arms 150 and 152 clockwise (Fig. 3) about the shaft 131.

The pawl 151, which is carried by the arm 150, is urged by a spring 159, which tends to move the pawl into a position where a bent-over portion of the pawl cam engages the notch in the segment 148 and couples the segment to the arm 150; however, in the normal position of the parts, a stud 160 on the subtraction control lever 100 engages an upward extension of the pawl 155 and holds the pawl out of coupling engagement with the segment 148, so that the operation of the arm 150 and the pawl 151 will be an idle one.

In a subtracting operation, the subtraction control lever 100 is rocked clockwise (Fig. 3) by the usual subtraction key as shown in said Patent No. 2,428,084 and moves the stud 160 forward in the machine, allowing the spring 159 to move the pawl 151 to engage its bent-over portion with the notch in the segment 148, coupling the segment 148 to the arm 150 for clockwise operation thereby. Since the segment 148 is secured to the shaft 131, the shaft will also be rocked clockwise in Fig. 3 and counter-clockwise in Fig. 6, which movement will through the cooperation of the roller 146 in the slot in plate 147 (Fig. 6) cause the shaft 131 to be shifted to the right, as explained earlier herein.

A second lever 165 (Fig. 3) pivoted on the stud 156, has a roller 166, which cooperates with another cam surface on the bottom of the full-stroke sector 72 and is rocked clockwise by the sector just before the sector returns to its home position near the end of the second half of a machine cycle of operation. The forward part of the lever 165 engages a stud 167 on the downwardly-extending restoring arm 149 and is effective, when the lever 165 is rocked clockwise, to impart restoring counter-clockwise (Fig. 3) movement to the shaft 131, which counter-clockwise movement will, through the cooperation of the cam slot in the plate 147 and the roller 146 on the lever 145, cause the shaft 131 to be restored to the left. Restoration of the shaft 131 to the left enables the studs 129, carried by the complementary levers, to recouple

the diverging levers 121 and the rack levers 126 for joint movement.

A spring 168 (Fig. 3), connected to the restoring arm 149 and the arm 150, is effective to 5 transmit the restoring movement of the arm 149 to arms 150 and 152 to return them to the position shown in Fig. 3.

A stud 143 (Fig. 6) on the lever 145 will rock a bell-crank 144 when the lever is rocked to subtracting position. The bell-crank 144 through the usual link 137 and yoke 138 will cause a ribbon supporting frame to be shifted, as fully disclosed in the White Patent No. 1,854,875, and my Patent No. 2,428,084, to cause subtracted amounts to be printed in red. In a manner similar to that shown in my Patent No. 2,428,084, a member on the ribbon supporting frame can engage a symbol type bar, a portion of which is shown at 139 (Fig. 4), and raise the bar to move a "minus sign" into printing position.

Totalizers

The #1 totalizer is similar to the one shown in the United States patents to Peters, No. 1,386,021, and White, No. 1,854,875, and contains a totalizer wheel 170 for each of the differentially operable means in the differential mechanism.

The totalizer wheels 170 are mounted in a totalizer supporting frame (Figs. 5 and 15), which 30 is composed of a plurality of plates 171 secured in proper spaced relation on a shaft 172. The frame thus formed is rockable about the trunnions 173 and 174, which extend into recesses in the ends of the shaft.

Extending through the plates 171 near their rear end is a rod 175, upon which the totalizer wheels 170 are individually rotatable. Each totalizer wheel has a pinion 176 connected to it on the right (Figs. 5 and 15) by a spacing sleeve and has a tens transfer cam 177 (Fig. 15) suitably connected to it on the left. The totalizer wheel unit thus formed occupies the space between adjacent plates 171, which serve to retain the unit in its proper lateral position. The trunnions 173 and 174 are adjustable in the side frames 50 and 51, respectively, to enable the totalizer to be moved crosswise in the machine to align the pinions with the actuating racks.

Suitable engaging means, which will be described later herein, rocks the totalizer frame 50 about the trunnions 173 and 174 at the proper time in the operation of the machine to engage and disengage the pinions 176 with and from the actuating racks 127.

The #2 totalizer contains a totalizer pinion 180 (Figs. 5 and 15) for each of the differentially operable means in the differential mechanism. These pinions are mounted in a totalizer supporting frame composed of a plurality of plates 181, which are freely mounted on the shaft 172 for pivotal movement thereon but which are retained in proper spaced relation by being secured to a rod 182, which extends across the width of the totalizer and below the shaft 172.

The pinions 180 have transfer cams 185 secured to their left sides by sleeves. The units thus formed by the pinions 180 and the cams 185 are individually rotatable on a rod 183, which is carried at the rear portion of the plates 181, the pinions being so located laterally between the plates as to be directly in front of the pinions 176 of the #1 totalizer, and the transfer cams 185 being so located as to be displaced a slight extent laterally from the transfer cams 177 of the #1 totalizer.

The rod 183 extends through suitable clearance openings 184 in the plates 171, which allow the supporting frame for the #2 totalizer to be rocked independently of the frame which supports the #1 totalizer, and enables the pinions 189 of the #2 totalizer to be engaged with and disengaged from the actuating racks 127 independently of the pinions 176 for the #1 totalizer.

Suitable novel engaging means differing from that for the main totalizers #1 and #3, which will be described later herein, rocks the supporting frame for the #2 totalizer about the shaft 172 at proper times in the operation of the machine to engage and disengage the pinions 189 with and from the actuating racks 127.

Alining plates 190 (Fig. 1) are supported in the rear of the pinions 176 and 189 by means of rods 191 and 192, secured in the side frames 50 and 51. Each of these plates has two alining teeth, the usual one which is engaged by the related pinion 176 of the #1 totalizer when that totalizer is in disengaged position, and an additional tooth which is located on a forward extension of the plate 190 and is engaged by the related pinion 189 of the #2 totalizer when that totalizer is in disengaged position.

The lower or #3 totalizer also is similar to the one shown in the United States patents to Peters, No. 1,386,021, and White, No. 1,854,875. This totalizer contains pinions 195 and the usual tens transfer cams 196 (Fig. 4), which are rotatable on a rod 197 carried by a totalizer supporting frame. The totalizer supporting frame is made up of plates 198, secured to the shaft 199, which is rockable on trunnions 200 and 201 (Figs. 3 and 6), secured, respectively, in the extensions 52 and 53. The pinions 195 are positioned laterally so as to be opposite the various actuating racks 133 carried by the downwardly extending rack levers 132, with which racks the pinions may be engaged at the proper time in the operation of the machine when the totalizer supporting frame is rocked by its totalizer engaging means.

Alining plates 202 (Fig. 1) are supported on rods 203 and 204 secured to the side frames 50 and 51 and the extensions 52 and 53 and have teeth with which the pinions 195 engage when the #3 totalizer is moved to disengaging position.

Tens transfer mechanism

The tens transfer mechanism associated with the #1 and the #2 totalizers is similar in many respects to the one shown and described in the above-mentioned United States patent to Peters, No. 1,386,021; however, it has been improved to enable the single transfer mechanism to be controlled selectively by either of these totalizers to effect tens transfer entries therein.

As explained earlier herein, each rack lever 126 carries, at its upper end, an actuating rack 127. The actuating rack 127 (Fig. 1) is mounted on the rack lever 126 for limited relative movement thereon by means of a pair of shouldered studs 210, which slide freely within a related pair of slots 211 in the lever 126. The rack 127 is urged rearwardly on the lever 126 by a spring 212, connected to a stud on the lever 126 and to a bent-over ear on a plate 213, secured to the rack 127 and tending to move the studs into engagement with the rear ends of the slots.

A transfer lever 214 is pivoted on a rod 215 carried by the plates 190 and is urged by a spring 216 into engagement with a transfer lever latch 217 pivoted on a rod 218 also carried by the

plates 190. In the normal position of the parts, as shown in Fig. 1, when no transfer is to be effected, a laterally-extending arm 220 (Figs. 1 and 2) on the transfer lever 214 for one denominational order engages a flange 221 (Fig. 2) on the plate 213 secured to the actuating rack 127 of the next higher denominational order and prevents the actuating rack 127 from moving its full extent rearwardly by one increment of movement as the rack lever 126 returns to its home position.

If, during an entry in the #1 or the #2 totalizer, the capacity of any denominational order is exceeded, the transfer cam secured to the pinion in that order will engage an associated bent-over ear on the transfer lever 214 and will rock the free end of the transfer lever 214 downwardly to move the arm 220 below the path of the flange 221 on the actuating rack 127 of the next higher order. The transfer lever latches 217 related to the operated transfer levers rock a slight extent counter-clockwise (Fig. 1) to engage over shoulders 222 on the upper surface of these transfer levers 214 to retain these transfer levers in their operated position, as is well-known in the art. When the racks 127 are returned with the rack levers 126, the flanges 221 on those racks which are controlled from the operated transfer levers, will move over the arms 220 on the operated transfer levers 214 and allow those racks to move farther to the rear than the ones which cooperate with arms on unoperated transfer levers. This further movement of the racks is sufficient to cause an additional value of "1" to be entered into their related totalizer pinions.

It is to be noted that the transfer levers 214 are long enough and have bent-over ears opposite the two upper totalizers, so that, when either totalizer is engaged with the actuating racks 127, its transfer cams can cooperate with the related bent-over ears on the transfer levers 214 to operate the transfer levers and allow tens transfer entries to be made in that particular totalizer. The instant construction, therefore, enables one tens transfer mechanism to serve both the #1 totalizer and the #2 totalizer.

The transfer lever latches 217 are restored early in the next machine cycle of operation by mechanism similar to that shown in my application Serial No. 586,360, which issued as United States Patent 2,592,436, on April 8, 1952. Each transfer lever latch 217 (Fig. 1) has an upwardly-extending arm 225, which lies closely behind a cross bar of a bail 226, which extends across the totalizers and is secured to a shaft 227 journaled in the side frames 50 and 51. Secured to the right end of the shaft 227 (Figs. 3 and 14) is a bell crank having one arm 228, which engages a limiting stud 229 on the side frame 51, and having another arm 230, to which the upper end of a link 231 is pivoted. The lower end of the link 231 is guided in an open-ended slot in a plate 232 secured to the side frame 51 and is urged into the forward portion of the slot in the plate 232 by a spring 233, which urges the link 231 downwardly and forwardly.

A stud 234 on the link 231 engages the bottom of the link 231 near the beginning of each machine cycle of operation and shifts the link 231 in the direction of its length to cause the bell crank and shaft 227 to be rocked counter-clockwise (Figs. 1 and 3) and move the cross bar of the bail 226 therewith into engagement with the upwardly-extending arms 225 of the transfer lever latches 217. This movement of the bail

226 will rock the latches 217 clockwise (Fig. 1) to clear the shoulders 222 on any operated transfer levers and allow these transfer levers to make an initial movement to their unoperated position. The transfer levers 214 will be completely returned to their unoperated position by the springs 216 when the flanges 224 move from over the arms 220 during the forward movement of the actuating racks 127.

This restoring mechanism is effective to restore the transfer lever latches when either the #1 or the #2 totalizer has been operated.

The tens transfer mechanism associated with the #3 totalizer also is similar to that shown in the patent to Peters, No. 1,386,021. The actuating racks 133 (Fig. 1), which are mounted for movement relative to the downwardly-extending rack arms 132, are also urged by springs 240 to make the further step of movement necessary to cause tens transfer entries. Transfer levers 241, pivoted on a rod 242 carried by the plates 202, are operated by transfer cams 196 (Fig. 4) and are retained in their operated position by transfer lever latches 243, which are pivoted on a rod 244, which also is carried by the plates 202. As in the Peters Patent No. 1,386,021, the transfer lever latches are restored by the engagement of arms 245 on the latches by the plates 198 of the totalizer supporting frame when the #3 totalizer is disengaged.

Totalizer engaging means

The totalizer engaging means for the #1 totalizer is shown in Figs. 4, 7 and 9 and is similar to the one shown in my copending application for United States Letters Patent, Serial No. 586,359, which was filed on April 13, 1945, which issued as United States Patent 2,562,049, on July 24, 1951.

The plate 171, forming the right-hand side of the #1 totalizer supporting frame, has a downward extension 250 (Figs. 4 and 7), which carries near its end a roller 251. The roller 251 extends into a cam slot 252 in a cam lever 253, which is pivotally mounted on a stud 254 extending inwardly from the side frame 51. The upper portion of the cam slot 252 is farther from the stud 254 than is the lower portion, so that, when the cam lever 253 is in the position in which the roller 251 is in the upper part of the cam slot 252, the totalizer supporting frame will have been rocked about the trunnions 173 and 174 to shift the pinions 176 into engagement with the actuating racks 127. When the cam lever 253 has been rocked about the stud 254 and the roller 251 is in the lower part of the slot 252, the supporting frame will have been shifted to disengage the pinions from the actuating racks.

A detent latch 255 (Fig. 4), pivoted on a stud 256 on the cam lever 253 and urged counter-clockwise by a spring 257, cooperates with a stud 258 on the inside of the frame 51 to locate the cam lever accurately in the position shown or the position in which the cam slot in the lever causes the totalizer to be disengaged from the actuating racks, and to yieldingly retain the cam lever 253 in either position.

The cam lever 253 is rocked by the following actuating mechanism to cause the totalizer to be engaged with and disengaged from the actuating racks.

Pivoted on the stud 254 (Figs. 7 and 9) adjacent the cam lever 253 is a lever 260 having a pin 261 engageable with a forward surface of an upwardly-extending arm 262 on the cam lever 253.

The upper end of the lever 260 carries a stud 263, upon which a coupling pawl 264 is pivoted. This coupling pawl 264 is urged by a spring 265 into engagement with a stud 266 on the upwardly-extending arm 262 of the cam lever 253. The pawl 264, by engaging the stud 266, retains the arm 262 with its forward surface in engagement with the stud 261 on the lever 260 and thereby latches the cam lever 253 to the lever 260 for operation therewith.

The lower end of the lever 260 has a stud 270 (Figs. 7 and 9) which is engaged by a forward notched portion of a pitman 271, which pitman, in turn, is pivotally connected to the upper end 15 of a three-armed lever 272 (Figs. 4, 7 and 11), pivoted on a stud 273 which extends inwardly from the right side frame 51.

The notch in the pitman 271 is held in engagement with the stud 270 on the lever 260, against the action of a spring 274, by the engagement of a roller 275 against an upwardly-extending arm 276 (Fig. 9) of the usual total control bell crank 277, pivoted on a stud 278 extending inwardly from the side frame 51.

The three-armed lever 272 has a stud 280 (Figs. 4, 11 and 16), which cooperates with a spring-urged pawl 281 pivotally mounted on an arm 282 on the rear shaft 61 and enables the three-armed lever to be rocked counterclockwise 20 (Figs. 4, 11 and 16) when the arm 282 is rocked counter-clockwise at the beginning of the operation of the machine. This counter-clockwise rotation of the three-armed lever 272 will, through the pitman 271 and the lever 260, rock the cam lever 253 clockwise to cause the totalizer to be disengaged from the actuating racks. A second stud 284 (Figs. 11 and 16), carried by the three-armed lever 272, cooperates with the pawl 281 near the beginning of the second half of the machine cycle and enables the pawl to rock the three-armed lever clockwise back to its home position. This clockwise rocking of the three-armed lever 272 will, through the pitman 271 and the lever 260, rock the cam lever 253 counter-clockwise (Figs. 7 and 9) to cause the totalizer to be engaged with the actuating racks. In this manner, the totalizer is rocked into engagement and out of engagement with the actuating racks 25 during normal adding and subtracting operations 30 if the totalizer has been selected for operation in a manner to be explained later herein.

A detent 283 (Figs. 4 and 16), pivoted on one side frame 51, carries a stud and is spring urged to force the stud into one or another of two notches in a forwardly-extending arm of the lever 272 to retain the lever in either of its rocked positions.

When the #1 totalizer is not selected for operation, a stud 285 (Fig. 7) is moved into the path 60 of movement of an upwardly-extending arm on the pawl 264. When the lever 260 is rocked clockwise (Fig. 7) near the beginning of the first half of the machine cycle, it will, through the pin 261, rock the cam lever 253 to disengage the totalizer. As the lever 260 and the pawl 264 near the end of their movement, the upwardly-extending arm of the pawl will engage the stud 285 and rock the pawl out of engagement with the stud 266, to uncouple the lever 260 from the cam lever 253. The pawl will be held out of engagement with the stud 266, so that the return movement of the lever 260 near the beginning of the second half of a machine cycle will not rock the cam lever 253, and the totalizer will remain out of engagement with the actuating racks during their 65 70 75

return movement, thereby preventing the entry of an amount therein.

Near the end of those operations in which the totalizer remains disengaged from the racks during their return movement and after the actuating racks have been returned to their home position, a finger 286 (Figs. 4 and 7) loose on the main shaft 73 will be engaged by a stud 287 on an arm 288 secured to the main shaft 73 and will be rocked clockwise (Figs. 4 and 7) thereby. When the finger 286 is thus rocked, its upper portion will engage a stud 289 on the cam lever 293 and rock the cam lever counter-clockwise to cause the totalizer to be engaged with the actuating racks.

This movement of the cam lever 293 moves the stud 286 into position where it is again engaged by the pawl 294 to recouple the cam lever 293 to the lever 299 for operation thereby.

The #1 totalizer, therefore, will be in engagement with the actuating racks at the end of every operation of the machine.

The totalizer-engaging means for the #3 totalizer is similar to the one for the #1 totalizer.

The plate 198 (Figs. 4, 9 and 11), forming the right side of the #3 totalizer supporting frame, has a rearward extension 295, carrying a roller 296, which extends into a cam slot 297 in a cam lever 298 pivoted on a stud 299 extending from the inside of the side frame 51. When the roller 296 occupies the forward end of the slot 297, the totalizer frame will have rocked about the trunnions 200 and 201 to engage the totalizer pinions 195 with the actuating racks 183, but, when the cam lever 298 has been shifted and the roller 296 occupies the rear end of the slot 297, the supporting frame will have been rocked to disengage the totalizer pinions from the actuating racks. A detent 300 (Fig. 4) locates and retains the cam lever 298 in either position.

Also pivoted on the stud 299 is a lever 301 (Figs. 9 and 11), which has a pin 302 engaging the lower surface of a forwardly-extending arm of the cam lever 298, has a pivoted pawl 303, engaging a stud 304 on the forwardly-extending arm of the cam lever, and has a stud 305 (Fig. 9), which is engaged by a notch in a rearward extension of a downwardly-extending pitman 306.

A spring 307 (Figs. 4 and 9), connected to the total control bell crank 277 and to the pitman 306, normally urges the lower end of the pitman 306 toward the front of the machine, but a stud 309 on the upwardly-extending arm 276 of the total control bell crank 277, engages a forward surface on the pitman in adding and subtracting operations and maintains the notch in the pitman in engagement with the stud 305 against the action of the spring 307.

The pitman 306 has its upper end pivoted to the forwardly-extending arm of the three-armed lever 272, is given a downward movement when the lever 272 is rocked counter-clockwise near the beginning of the first half of a machine cycle of operation, and is returned upwardly when the three-armed lever 272 is rocked clockwise near the beginning of the second half of the machine cycle of operation.

When the #3 totalizer is selected for operation, this downward and upward movement of the pitman will be effective, through the lever 301, to rock the cam lever 298 and cause the #3 totalizer to be disengaged from the actuating racks during the first half of a machine cycle of operation and be engaged with the racks during the second half of this cycle.

As in the case of the #1 totalizer, when the #3

totalizer is not selected for operation, a stud 310 is positioned in the path of movement of an arm on the pawl 303 to disengage the pawl from the stud 304 and uncouple the cam lever 298 from the lever 301 after the cam lever has been shifted to cause the totalizer to be disengaged from the actuating racks. The totalizer will remain disengaged from the actuating racks and will receive no entry as the racks return to their home position.

In those operations in which the #3 totalizer remains disengaged from the racks during their return movement, it will be engaged with the racks after they have returned to their home position. This is accomplished by a bell crank (Figs. 4 and 11) pivoted on a stud 315 on the side frame 51, the bell crank having a forwardly-extending arm 316 (Fig. 11), which engages a stud 317 on the cam lever 298, and having an upwardly-extending arm 318 carrying a roller 319, which is engaged by the rear edge of the arm 282 on the rear shaft 61. As the arm 282 moves counter-clockwise (Fig. 4) at the beginning of a machine operation, a spring 320 will rock the bell crank counter-clockwise until the arm 316 engages a stud 321 on the side frame 51. This movement of the bell crank will move the arm 316 from its engagement with the stud 317 on the cam lever 298 and will allow the cam lever to be shifted clockwise when the totalizer is disengaged from the actuating racks. Near the end of the movement of the arm 282 to its home position, it will engage the roller 319 and rock the bell crank clockwise, causing the arm 316 on the bell crank to engage the stud 317 on the cam lever 298 and rock the cam lever to the position in which it causes the totalizer to be engaged with the racks.

The restoring movement of the cam lever 298 moves the stud 304 into a position where the pawl 303 engages it and recouples the cam lever 293 to the lever 301 for further operation therewith.

The #3 totalizer, therefore also will be engaged with the racks at the end of each operation of the machine.

The totalizer-engaging means for the #2 or extra totalizer is located at the left-hand side of the machine and is somewhat different from the engaging means for the #1 and the #3 totalizers.

The plate 181, forming the left side of the #2 totalizer supporting frame (Fig. 5), has a downward extension 325, which carries a roller 326 near its lower end. The roller 326 extends into a cam slot 327 (Figs. 6 and 8) in a cam lever 328, which is pivotally mounted on a stud 329 extending inwardly from the left side frame 50. This cam slot 327 will cause the #2 totalizer supporting frame to be positioned with the pinions 180 in engagement with the actuating racks 121 when the roller 326 occupies the lower portion of the slot, and will cause the totalizer supporting frame to be positioned with the pinions 180 out of engagement with the actuating racks 121 when the roller 326 is in the upper end of the slot.

A detent 330 (Fig. 6), mounted on a pin 331 on the cam lever 328, is urged clockwise into engagement with a stud 332 on the side frame 50, to retain the cam lever 328 in either of these positions.

The pin 331 (Figs. 6 and 8) on the cam lever 328 extends through a suitable opening in the side frame 50 and into the path of movement of a pawl 335, which is pivotally mounted on a segment 336 secured to the main shaft 73. The pawl 335 is urged by a spring 337 into a position in which the longest dimension of the pawl is substantially radial to the shaft. The free end of the pawl 335 is provided with a shoulder 338.

which, in the home position of the pawl, as shown in Figs. 6 and 8, lies under the pin 331. Early in the movement of the segment 336, clockwise in Fig. 6 and counter-clockwise in Fig. 8, the shoulder 338 on the pawl will engage the pin 331 and will shift the cam lever 328 to cause the upper portion of the cam slot 327 to cooperate with the roller 326, thereby causing the supporting frame to be rocked to disengage the pinions 180 from the actuating racks 127 if not already disengaged. This disengagement of the #2 totalizer occurs in adding or subtracting operations before the racks begin their forward movement.

A link 340, which has a stud 341 in its forward end, is pivoted at its rear end to the cam lever 328. When the #2 totalizer is selected for operation, as will be explained more fully hereinafter, the stud 341 is positioned opposite a notch 342 in the edge of the segment and in the path of movement thereof. As the segment approaches the end of its clockwise movement (Fig. 6) near the end of the first half of a machine cycle of operation, the notch 342 in the segment will engage the stud 341, and the continued movement of the segment will pull the link 340 forwardly to rock the cam lever 328 (counter-clockwise in Fig. 6 and clockwise in Fig. 8), to cause the lower end of the cam slot 327 to engage the roller 326, thereby rocking the supporting frame and engaging the pinions 180 with the actuating racks 127 after the actuating racks have completed their forward movement. The pinions remain in engagement with the actuating racks and in adding and subtracting operations will receive entries during the return movements of the racks.

A spring 343 (Fig. 6) connected between an extension of the segment 336 and the side frame, is utilized to assist in the restoration of the main shaft 73 to its normal position.

Totalizer selecting mechanism

The mechanism for selecting any one of the totalizers for operation is shown in Figs. 3, 4, 6, 7, 8 and 11 and includes a totalizer selecting lever 350 and a plurality of trains of mechanism operated thereby which extend to and control the operation of the engaging means for the various totalizers. In these figures, the selecting mechanism is shown in the position in which the #2 totalizer is selected for operation.

The totalizer selecting lever 350 (Fig. 3) is pivotally mounted on the end of the stud 103 which extends from the side plate of the key-board, and is settable to any of three positions, in each of which it will control the selection of a different totalizer. During the operation of the machine, the totalizer selecting lever is retained in its set position by means of a projection 349 on the right end of the slide 116, which projection enters into suitable holes in the lever when the slide 116 moves to the right of the machine near the beginning of an operation of the machine.

Stud 351 (Figs. 7, 8, 10, 11 and 14) in the lower end of the lever cooperates with control surfaces formed on the forward portion of the levers 352, 353, 354 and 355, pivoted on a stud 356 extending from the outside of the side frame 51. The levers 353, 353 and 355, respectively, control the positioning of the symbol-printing type bar and the operation of the engaging means for the #1, the #3 and the #2 totalizers.

Levers 353 (Fig. 7), which controls the engaging means for the #1 totalizer, is urged clockwise (Fig. 7) by a spring 357, which maintains the control surface on the forward portion of the

lever in engagement with the stud 351. An upwardly-extending arm 353 on the lever 353 extends through a suitable opening in the side frame 51 and carries the stud 285 which controls whether or not the coupling pawl 264 will remain in engagement with the stud 286. When the totalizer selecting lever 350 is in either its #2 or its #3 totalizer selecting position, the stud 351 will position the lever 353 so that the stud 285 will be in the path of movement of the coupling pawl 264 and will disengage the pawl from the stud 286 after the pitman 271 has rocked the lever 260 and the cam lever 253 to disengage the #1 totalizer. With the pawl 264 thus disengaged, the return movement of the pitman 271 and the lever 269 will be ineffective to shift the cam lever 253, and the totalizer will remain disengaged from the actuating racks during their return movement, thereby preventing the #1 totalizer from receiving entries when either the #2 or the #3 totalizer has been selected for operation. As explained earlier herein, the cam lever 253 will be rocked by the finger 286, at approximately the end of the machine cycle of operation, to cause the totalizer to be engaged with the actuating racks.

When the totalizer selecting lever 350 is in its #1 totalizer selecting position, the lever 353 will be positioned with the stud 285 out of the path of movement of the coupling pawl 264, and the cam lever 253 remains coupled to the lever 260 to be operated thereby and cause the totalizer to be engaged with the actuating racks at the beginning of the second half of a machine cycle, thus enabling entries to be made into the #1 totalizer as the racks return to their home positions during the second half of a machine cycle in adding and subtracting operations.

Lever 354 (Figs. 3, 11 and 14), which controls the engaging means for the #3 totalizer, has a downwardly-extending link 360 pivoted at its rear end. A stud 361 in one arm of a bell crank 362, pivoted on a stud 363 on the outside of the side frame 51, extends through a slot 364 in the lower end of the link 360 and is urged into engagement with the lower end of the slot by a spring 365. The spring 365, by urging the stud 361 into engagement with the bottom of the slot 364, exerts a pull on the link 360 which is effective to maintain the control surface at the front end of lever 354 in engagement with the stud 351 on the totalizer selecting lever 350.

The other arm of the bell crank 362 carries the stud 360, which extends through a suitable opening in the side frame 51 and cooperates with the coupling pawl 303 to control the coupling of the cam lever 298 to the lever 301 for operation thereby when the lever 301 is operated by the pitman 306.

When the totalizer selecting lever 350 is in either its #1 or its #2 totalizer selecting position, the stud 351 will cause the lever 354, the link 360, and the bell crank 362 to assume the position shown in Figs. 3 and 11, in which position the stud 360 will be in the path of movement of the coupling pawl 303 and will disengage the pawl from the stud 304 after the pitman 306 has rocked the lever 301 and the cam lever 298 to disengage the #3 totalizer. With the pawl 303 thus disengaged, the return movement of the pitman 306 and the lever 301 will be ineffective to shift the cam lever 298, and the totalizer will remain disengaged from the actuating racks during their return movement, thereby preventing the #3 totalizer from receiving entries when

either the #1 or the #2 totalizer has been selected for operation.

In those operations in which the #3 totalizer remains out of engagement with the actuating racks 133 during their return movement, the 5 arm 316 will engage the stud 317 on the cam lever 298 near the end of the machine cycle of operation, as explained earlier herein, and will rock the cam lever to engage the totalizer with the racks after they have returned to their home 10 position.

When the totalizer selecting lever 359 has been moved to its #3 totalizer selecting position, the stud 351 will be opposite a low portion of the control surface on the lever 354 and will allow 15 the spring 365 to shift the bell crank 362 to move the stud 318 out of the path of movement of the pawl 393, so that the cam lever 298 will remain coupled to the lever 351 to be operated thereby and cause the totalizer to be engaged with the 20 racks at the beginning of the second half of a machine cycle. This enables entries to be made into the #3 totalizer in adding and subtracting operations as the racks return to their home positions during the second half of the machine 25 cycle of operation.

Lever 355 (Figs. 3, 6 and 8), which cooperates with the stud 351 on the lever 359 to control the engaging means for the #2 totalizer, has pivotally connected thereto, the upper end of a link 370, 30 whose lower end is pivotally connected to an arm 371 secured on the right-hand end of a shaft 372, which extends across the machine and is journaled in the extensions 52 and 53. Adjacent its left end, the shaft 372 has secured thereto an arm 373, to which lower end of a link 374 is pivotally connected. The upper end of the link 374 (Figs. 6 and 8) has therein a slot 375, which cooperates with a stud 376 on a lever 377 pivoted on a stud 378, to enable the link 374 to be moved 40 up and down in a substantially vertical path.

The link 374 has a forwardly-extending finger 381, which lies under the stud 341 and enables the link 374 to control the positioning of the stud 341 relative to the notch 342 in the forward edge of the segment 336. A spring 382 (Fig. 6), connected to the stud 341 and to the link 374, maintains the stud in engagement with the finger 381.

When either the #1 or the #3 totalizer is selected for operation, the stud 351 will engage one or the other of the end portions of the control surface on the lever 355, thereby rocking the lever to operate the parts connected thereto, which causes the link 374 to be moved upwardly to raise the stud 341 out of the path of movement of the segment 336. As explained earlier herein, if the stud 341 is in the path of movement of the segment 336, the segment will engage the stud 341 near the end of the first half of a machine cycle of operation in adding and subtracting operations and will pull the link 340 forwardly to rock the cam lever 328 and cause the totalizer to be engaged with the actuating racks to be operated thereby and receive entries during the return movement of the racks. Accordingly, when either the #1 or the #3 totalizer has been selected for operation and the stud 341 has been moved upwardly out of the path of movement of the segment 336, the segment cannot pull the link 340 forwardly, and the totalizer will remain disengaged from the racks during their return movement, thereby preventing the #2 totalizer from receiving entries when either the #1 or the #3 totalizer has been selected for operation.

When the #2 totalizer is selected for operation, the positioning of the totalizer selecting lever 350 will place the stud 351 in cooperative relation with the central portion of the control surface on the lever 355. This allows the link 374 to move to its lower position to place the stud 341 where it can be engaged by the notch 342 in the segment 336 and enables the segment to pull the link 340 forwardly to cause the totalizer to be engaged with the actuating racks before they begin their return movement, thus enabling entries to be made into the totalizer.

It is seen that the totalizer selecting mechanism, by selectively controlling the totalizer engaging means, can control which totalizers will remain out of engagement with the actuating racks during their return movement and can thereby select any one of the three totalizers to receive entries in adding and subtracting operations.

A type bar 385 (Fig. 10) is set under control of the totalizer selecting lever 350 to cause the digits "1," "2," or "3" to be printed to indicate which of the totalizers is selected for operation. As the totalizer selecting lever is positioned to select a desired one of the totalizers, the stud 351 thereon will cooperate with the control surface at the front of the lever 352 to enable the lever to be positioned in a corresponding one of three positions.

The lever 352 has a rearward extension which lies under a stud 386 in one arm 387 (Figs. 10 and 14) of a yoke pivoted on a stud 388, which extends from the inside of the side frame 51. The arm 387 extends through a suitable opening in the side frame 51, and its forward end is urged downwardly by a spring 389, which is effective, through the engagement of the stud 386 with the rearward extension of the lever 352, to maintain the control surface at the front of the lever 352 in engagement with the stud 351 on the totalizer selecting lever 350.

The other arm 390 (Figs. 10 and 14) of the yoke has therein a slot 391, into which extends a stud carried by a lever 393 pivoted at its front end on a stud 394 extending from the usual right printer frame 395, a portion of which is shown in Fig. 10. The rear end of the lever 393 is bifurcated and engages a stud 396 on the side of the type bar 385.

Type elements bearing the digits "1," "2" and "3" are located on type bar 385 with the digit "1" above the digit "2" and with the digit "3" below the digit "2." When the lever 352 is positioned under control of the totalizer selecting lever 350, it will, through the yoke and the lever 393, cause the type bar to be moved up or down to bring the proper type element in printing position, thereby enabling the proper digit to be printed to indicate which totalizer has been selected for operation.

Total-taking control mechanism

In the instant machine, totals are taken in the usual manner by causing the totalizer from which the total is being taken to be in engagement with the racks of the various differentially operable means during their movement in the first half of a machine cycle of operation, so that the pinions of the totalizer will be rotated by the differentially operable means in a direction reverse to that in which they are rotated in receiving entries during adding and subtracting operations. The various pinions will be rotated until they reach their zero position, when a radial portion of their related transfer cams will

engage corresponding bent-over ears on the transfer levers to prevent further movement of the pinions and the differentially operable means with which they are engaged. As a result of this operation, the total will be cleared from the totalizer and the differentially operable means will be set according to the total, positioning the type bars so that this total can be printed.

Because the instant machine is provided with three totalizers, it is necessary that the totalizer selecting mechanism cooperate with the total-taking control mechanism to cause any one of the totalizers, but only the selected one, to be in engagement with the differentially operable means as they are moved during the first half of a machine cycle to insure that these means will be set correctly to represent the total.

The total-taking control mechanism of the instant machine is similar in many respects to that usually found in machines of the type in which the invention is embodied, which mechanism, when operable, causes the several differentially operable means to be released for operation, causes a cycle of operation to be initiated, and causes totalizer-engaging means to be controlled to cause a totalizer to be in engagement with the racks of the differentially operable means during their forward movement to be cleared thereby and control the differential setting of the differentially operable means and to be disengaged from the racks of the differentially operable means before they begin their return movement.

The total-taking control mechanism can also be operated to cause a sub-total operation which is similar to a total-taking operation but in which the totalizer is in engagement with the differentially operable means during their forward movement to control their position according to the amount therein and is in engagement during their return movement to enable the total to be restored therein.

The usual total lever 400 (Figs. 4, 9 and 14) is secured on a shaft 401, which extends across the machine and is journaled in the side frames 50 and 51. The usual space stroke locking lever 402 (Figs. 4 and 14) cooperates with the total lever 400, in the manner explained fully in the United States patent to Peters, No. 1,646,105, to compel a tens transfer restoring operation of the machine to be made before the total lever can be operated after any amount-entering operation.

To cause a total-taking operation to take place, the lever 400 is rocked clockwise (Fig. 9) to shift the upper end of a link 403 forwardly and upwardly, causing the link to move upwardly and rock the total control bell crank 277 counter-clockwise against the action of a spring 404 (Fig. 4).

When the bell crank 277 is rocked, it will pull a link 405 rearwardly. The link 405 is pivotally connected at its forward end to a lever 406 (Fig. 4) pivoted on a stud 407 on the inside of the side frame 51. As the link is moved rearwardly by the operation of the total lever 400, the lever 406 is rocked counter-clockwise (Fig. 4), and a cam surface at the upper end of the lever will press on a roller 408 on a rearwardly-extending arm 409 of the key release bail 113 to rock the bail. The bail 113 has thereon the usual fingers, which coact with the zero stop levers 112 (Fig. 1), when the bail is rocked, and shift them from in front of the stop bars 120 to free the differentially operable means for operation, as fully shown and

described in the United States patent to Fried, et al., No. 1,857,299, which issued May 10, 1932. As explained earlier herein, fingers on the bail 113 cooperate with the latching plates 114 to release any depressed keys upon the rocking of the bail. Accordingly, the operation of the bail, when the total lever is operated to cause a total-taking operation to take place, will release any amount key which might have been depressed and will free the various differentially operable means for operation during the total-taking operation.

When the link 405 is pulled rearwardly, a stud 410 (Fig. 4) thereon, cooperating with the bifurcated lower end of a bell crank 411, will cause the bell crank 411 to rock about the stud 412 extending inwardly from the side frame 51.

As the bell crank 411 is rocked, a forwardly-extending finger 418 thereon will move below a flange 419 on the non-add and total lever latch 102. This movement of the bell crank 407 will also cause a stud 413 thereon to engage a latch-retaining plate 414 and rock the plate about the stud 412 to remove a finger on the plate from blocking relation with the flange and allow a spring 415 to rock the latch 102. The latch 102, when thus rocked, moves the flange 419 over the finger 418 on the bell crank 411, thereby retaining the bell crank 411 and the total lever 400, connected thereto, in their moved positions. The latch 102 will retain these parts in their moved positions until the usual roller 416 (Fig. 3) on the full stroke sector 72 engages the by-pass pawl 417 (Fig. 4) on the latch 102 soon after the beginning of the return stroke of the sector 72, and rocks the latch 102 clockwise (Fig. 4) to move the flange 419 out of latching relation with the finger on the bell crank 411, thereby allowing the spring 404 to return the total lever 400 and parts connected thereto to their normal positions.

In the movement of the non-add and total lever latch 102 to its latching position, the extension 101 thereon will engage the stud 98 (Fig. 3) and will rock the trip lever 85 to initiate a cycle of operation of the machine as explained earlier herein.

A counter-clockwise movement (Fig. 4) of the total lever 400 will cause a sub-total operation to take place. This movement will raise the link 403 and operate the other parts as described above, and in addition will control the totalizers engaging means for the selected totalizer to cause the totalizer to remain in engagement with the differential means during the return movement of the differential means as will be explained hereinafter.

The usual stud 483 on the total lever 400 engages the usual three armed lever 492 to rock the lever different extents for a total taking operation and for a sub-total taking operation. Lever 492 through the usual coupling lever 489 positions the symbol type bar 139 in a manner shown fully in the Peters Patent No. 1,386,021, to place the total or sub-total symbol in printing position as required.

The above controls operate in the same manner in all total-taking operations and are not affected by the selection of the totalizer from which the total is being taken.

The manner in which the totalizer-selecting mechanism and the total-taking control mechanism cooperate to control the engaging means to enable totals to be taken from the various totalizers will now be explained.

The controls for the #1 totalizer engaging means will be considered first.

It will be recalled that when the totalizer selecting mechanism is set for the selection of the #1 totalizer, the stud 351 on the totalizer selecting lever 350 will be opposite the low portion of the control surface at the front of lever 353, and the spring 357 will rock the lever 353 clockwise a slight extent, from the position shown in Fig. 7. In this clockwise position the stud 285 has moved out of cooperative relation with the pawl 264 and the lever 260 remains coupled to the cam lever 253 during the second half of a machine cycle. Also, in this clockwise position of the lever 353, a rearward extension thereon will move downwardly away from a stud 425 on a lever 426 pivoted on a stud 427 on the outside of the side frame and will allow the lever 426 to make a slight counter-clockwise movement.

The lever 426 is formed with a bent over portion 428 which extends through a suitable opening in the side frame 51 and behind a stud 429 on a lever 430 pivoted on the stud 273. When the lever 426 is rocked counter-clockwise, the bent over portion 428 will move to the rear of the machine sufficiently to allow the lever 430 to be rocked clockwise (Fig. 7).

The lever 430 has an edge 431 on a forwardly-extending portion thereof which overlies the roller 275 on the pitman 271 and which holds pitman 271 in engagement with stud 270 while totals are being taken in the #2 and #3 totalizers, as will become apparent.

When the bell crank 277 (Fig. 9) is rocked by the total lever 400, the upwardly-extending arm 276 moves away from the stud 275 on the pitman 271 and the spring 274 will raise the forward end of the pitman to remove the notch therein from engagement with the stud 270 on the lever 260 before the pitman is given its forward movement.

Since the totalizer selecting mechanism is set to select the #1 totalizer, the lever 430 will not prevent the disconnection of the pitman 271 from the lever 260 but will be rocked clockwise by the roller 275 as the forward end of the pitman 271 is raised by the spring 274.

With the pitman thus disconnected from the lever 260, the #1 totalizer will not be shifted out of engagement with the racks of the differentially operable means and will be restored to zero thereby to control the setting of the differentially operable means according to the total during the first half of a machine cycle of operation as is customary in total-taking operations.

As the pitman 271 reaches its farthest extent of forward movement a notch 435 in an extension thereof (Figs. 7 and 9) will engage a stud 436 (Fig. 9) on the upper end of the lever 260, and the return movement of the pitman will rock the lever 260 and the cam lever 253 coupled thereto, clockwise (Fig. 7), to cause the zeroized totalizer to be disengaged from the racks of the differentially operable means before the racks begin their return movement in the second half of a machine cycle of operation.

The finger 286 (Fig. 7) loose on the main shaft 13 will be operated to rock the cam plate 253 near the end of the machine cycle, as explained earlier herein, and will thereby cause the zeroized totalizer pinions to engage the racks after the racks have completed their return movement.

The above control of the totalizer engaging means for the #1 totalizer will be effective in all total-taking operations in which the #1 totalizer

is selected for operation. When either the #2 or #3 totalizer has been selected for operation, the stud 351 on the totalizer-selecting lever 350 will be opposite the higher portion of the control surface on the lever 353, as shown in Fig. 7, and the lever 353 will have been rocked counter-clockwise from its #1 totalizer-selecting position to the position shown. With the lever 353 in this position, the stud 285 will have moved forward into position to cooperate with the pawl 264 and uncouple the lever 260 from the cam lever 253 near the end of the first half of a machine cycle of operation, and the rearward extension of the lever 353 will have moved upward and will have positioned the lever 426 with its bent over portion 428 immediately behind the stud 429 on the lever 430 to block any substantial clockwise movement of the pitman 271.

When either the #2 or the #3 totalizer is selected for operation and the total lever 400 rocks the total control bell crank 277 to move the arm 276 from engagement with the roller 275, the lever 430, being blocked against movement, will, through its engagement with the roller 275, block the raising of the forward end of the pitman 271 by the spring 274 and will cause the notch in the pitman to remain in engagement with the stud 270 on the lever 260.

Since the notch in the pitman remains in engagement with the stud 270, the forward movement of the pitman will rock the lever 260 and cam lever 253 to disengage the totalizer pinions from the racks before the racks begin their forward movement, and since the lever 260 is uncoupled from the cam lever 253 near the end of the first half of a machine cycle, thereby preventing the return movement of the pitman from rocking the cam lever 253 to cause the engagement of the totalizer pinions with the racks before the racks make their return movement. Therefore the #1 totalizer will remain out of engagement with the racks during total-taking operations when either the #2 or #3 totalizer is selected for operation and its setting will not be affected.

The controls for taking a sub-total from the #1 totalizer are substantially the same as above, but when the total lever 400 is rocked counter-clockwise (Fig. 9) and shifts the link 403 to operate the total control bell crank 277 and the slide 405 and associated parts the same as in a total-taking operation, it moves the upper end of the link 403 rearwardly. The rearward movement of link 403 positions a roller 434 thereon in the path of the pitman 271 to limit its upward movement so the notch 435 will not engage the stud 436 on the lever 260. This will prevent the pitman from causing the #1 totalizer from being disengaged from the racks of the differentially operable means during the return movement of the differentially operable means. The totalizer accordingly will remain in mesh with the racks in both these forward and return movements as is necessary in a sub-total taking operation.

The controls for the #3 totalizer engaging means in a total-taking operation are similar to those for the #1 totalizer.

When the totalizer selecting mechanism is set for the selection of the #3 totalizer, the stud 351 on the totalizer selecting lever 350 will be opposite the low portion of the control surface at the front of lever 354 (Fig. 11) and the spring 365 can, through the link 369, rock the lever clockwise a slight extent from the position shown in Fig. 11. This movement of the lever 354 and link 360 will allow the bell crank 362 to rock clockwise

to move the stud 310 out of cooperative relation with the pawl 303 and enables the lever 301 to remain coupled to the cam lever 298.

The clockwise movement of the lever 354 (Fig. 11) will cause a link 437 pivotally connected to the forward part of the lever 354 to move and rock a blocking member 438 counter-clockwise. This blocking member 438 holds pitman 306 in normal position shown in Fig. 11, when a total is being taken in the #1 or #2 totalizer, during which time stud 308 (Fig. 9) is ineffective. The blocking member 438, which is connected to the link 437 by a pin and slot connection, is pivoted on a stud 439 on the inside of the side frame 51 and has an edge 440 which cooperates with a stud 441 on the pitman 306 except when the #3 totalizer has been selected for operation, at which time the rocking of the member 438 by the link 437 moves the edge 440 away from the stud 441.

When the total control bell crank 277 (Fig. 9) is rocked by the total lever 400 in a total-taking operation, the stud 308 on the upwardly-extending arm 276 of the bell crank moves away from the front edge of the pitman 306 and allows the spring 307 to move the lower end of the pitman forwardly to remove the notch therein out of engagement with the stud 305 on the lever 301 early in the machine cycle of operation, as controlled by lever 445, before the pitman is able to move the lever 301.

Lever 445 (Fig. 11) pivotally mounted on the stud 315, and yieldably connected to the lever 318, cooperates with a stud 446 on the pitman 306 to control the time of disengagement and engagement of the notch and the stud 305 during the cycle of operation of the machine.

With the notch in the pitman 306 disengaged from the stud 305, the lever 301 and cam lever 298 will not be rocked by the downward movement of the pitman 306 and the pinions of the #3 totalizer will remain in mesh with the racks of the differentially operable means during the forward movement thereof to be zeroized thereby and control the setting of the differentially operable means according to the several digits of the total.

As the pitman 306 moves downward, a notch 447 in a forward arm thereof engages a stud 448 (Fig. 9) on the lever 301 and enables the return movement of the pitman to rock the lever 301 clockwise (Fig. 9) to disengage the #3 totalizer from the racks before they begin their return movement.

When the total lever 400 is rocked counter-clockwise (Fig. 9) to condition the machine for a sub-total operation, it shifts the upper end of the link 403 rearwardly and positions a stud 450 thereon so that it will prevent the notch 447 in pitman 306 from engaging the stud 448, and consequently will prevent the pitman 306 from causing the #3 totalizer to be disengaged from the racks before they return to their home position. The totalizer therefore will remain in engagement with the racks during both their forward and return movements, as is required in sub-total operations.

If the #1 or #2 totalizer is selected for operation, the blocking member 438 (Fig. 11) prevents the pitman 306 from being disengaged from the stud 305 in the total-taking operation, so that the #3 totalizer is immediately disengaged from the racks, and the stud 310 uncouples the pawl 303 from the stud 304 to allow the totalizer to remain out of engagement with the racks until they have

returned to their home position as explained earlier herein.

Finally, the controls for the #2 totalizer engaging means in total-taking operations will be considered.

When the #2 totalizer is selected, the stud 351 on the lever 350 will be opposite the low portion of the control surface at the forward end of lever 355 (Fig. 8) and, as explained earlier herein, will allow the spring 380 to move the link 374 downwardly. Downward movement of the link 374 will rock the lever 377 counter-clockwise (Fig. 6) about its pivot 378.

Pivoted to the rear end of the lever 377 is a downwardly-extending link 456 (see also Fig. 8) which has a stud 457 in its lower end. As the lever 377 is rocked counter-clockwise (Fig. 6) the stud 457 carried by the link 456 will be moved in front of an edge 458 at the lower end of a lever 459 pivoted on stud 460 on the side frame 50.

A spring 461 (Fig. 8) tensioned between the lever 377 and the link 456 urges the link counter-clockwise (Fig. 8) into engagement with the housing of motor 55 as is best shown in Fig. 12.

Pivoted on the lever 459 is a cam lever 462 (Fig. 6) having forward finger 463 which extends over a stud 464 on the lever 377 and is urged into engagement therewith by a spring 465. Counter-clockwise movement (Fig. 6) of the lever 377, on selection of #2 totalizer, will allow the cam lever 462 to rock clockwise (Fig. 6) on the lever 459 to bring a forward edge 466 thereof in position to engage the stud 331 on the cam plate 328, if the cam plate is in position in which the totalizer has remained disengaged from the racks at the end of a previous operation. Movement of the total lever will then engage the #2 totalizer as will be explained.

Pawl 470 pivoted on the segment 336 on shaft 407 is urged by a spring 471 into a position in which the longest dimension of the pawl is substantially radial to the shaft. The pawl 470 is held in its normal position (Figs. 6 and 8) against a stud 472 secured in the side frame 50.

A second lever 475 (Fig. 6) pivoted on the stud 460 has a stud 476 in its lower end which normally is in position to prevent the pawl 470 from engaging the stud 331 and rocking the cam lever 328 to disengage the #2 totalizer at the beginning of the return stroke of the segment.

Levers 459 and 475 (Fig. 6) have cam surfaces at their upper ends which cooperate with a stud 477 on an arm 478 secured to the end of the shaft 401 on which the total lever 400 is secured. When the total lever 400 is operated to initiate a total-taking operation, the arm 478 will rock counter-clockwise (Fig. 6) causing the lever 459 to rock counter-clockwise and allowing the lever 475 to rock counter-clockwise (Fig. 6).

Counter-clockwise movement of lever 459 will cause the cam lever 462 thereon to engage the stud 331, if the totalizer is disengaged, and directly rock the cam plate 328 to engage the #2 totalizer with the racks before they begin their forward movement. At the same time, the edge 458 on the lever 459 will move the stud 457 forward to engage the pawl 335 and move it out of cooperative relation with the stud 331 to prevent the pawl from contrarily disengaging the totalizer during the initial movement of the segment.

The rocking of lever 475 will position the stud 476 so that it will cause the pawl 470 to be effective to disengage the totalizer before the return stroke of the actuator racks.

Accordingly, with the #2 totalizer selected, the

operation of the total lever 400 to initiate a total-taking operation will, through the arm 478 and stud 477, rock the lever 459 to cause the cam lever 462 thereon to rock the cam lever 328, to immediately engage the totalizer with the racks if the totalizer had been left disengaged in a previous operation, and to cause the edge 458 to shift the stud 457 and move the pawl 335 out of cooperation with the stud 331 on the cam lever 328 to prevent the totalizer from being disengaged from the racks at the beginning of the forward movement of the segment 336. These controls will insure that the totalizer will be in engagement with the racks only during their forward movement and will be reset thereby.

Arm 478 and stud 477 will position the lever 475 where the stud 476 thereon will locate the pawl 470 so that it will engage the stud 331 and rock the cam lever to disengage the totalizer from the racks before they begin their return movement.

In a sub-total taking operation, the arm 478 is rocked clockwise (Fig. 6) and causes the lever 459 to be operated as in a total-taking operation. The lever 475 is maintained in its normal position where stud 476 will engage the pawl 470 and prevent it from engaging the stud 331 to shift the totalizer out of engagement with the racks of the differentially operable means before they begin their return movement. Under these circumstances the totalizer will remain in engagement with the racks during both their forward and return movements as is required in a subtotal taking operation.

When either the #1 or the #3 totalizer is selected, the link 374 will be in its upper position as explained earlier herein. In this position the lever 377 will have been rocked clockwise (Fig. 6) to raise the stud 457 out of engaging relation with the edge 458 and will have rocked the cam lever 462 upward out of engaging relation with the stud 331. Under these conditions the #2 totalizer will not be engaged by the cam lever 462 when the lever 459 is moved by the total lever and the pawl 335 will remain in engagement with the stud 331 and will disengage the #2 totalizer immediately upon the movement of the segment 336.

As explained earlier, the stud 341 is moved by link 374 out of cooperation with the segment 336 when either the #1 or #3 totalizer is selected, so the #2 totalizer will remain disengaged during the return movement of the racks. Since the totalizer is already disengaged from the racks, the pawl 470 will be ineffective even though the lever 475 is set to a position where the pawl would be effective in a total-taking operation with the #2 totalizer selected.

Non-add control mechanism

In the instant machine, non-add operations may be performed when any one of the three totalizers is selected for operation and the selected totalizer will be prevented from engaging the racks to receive an entry therefrom.

Non-add operations are initiated by pushing the upper end of a Non-add lever 481 (Figs. 4, 8, 14 and 16) rearwardly. The Non-add lever 481 is pivoted on the alining plate supporting rod 191 carried by the side frames 50 and 51 and has pivoted thereto the upper end of a non-add link 483, the lower end of which is pivoted to a latch plate 484 rotatable about the stud 412. As the Non-add lever 481 is rocked, it will give the latch plate 484 a preliminary rocking movement clockwise (Fig. 4) to move a latching projection

485 above the flange 419 on the non-add and total lever latch 102. As the plate 484 is given this preliminary movement a stud 486 thereon will engage the latch retaining plate 414 and rock it to remove the finger thereon from blocking relation with the flange 419 to allow the latch 102 to be moved to latching position by the spring 415. As the latch is thus moved, the finger 101 thereon will initiate a cycle of operation of the machine as explained earlier herein.

The initial movement of the latch plate 484 moves a camming extension 487 (Fig. 4) thereon into the path of the stud 287 on the arm 288. The stud 287 engages the extension 487 and gives an additional clockwise movement to the latch plate 484 at the proper time in the operation of the machine. This additional movement of the latch plate 484 causes an additional upward movement of the link 483.

This operation of the link 483 is the same regardless of which totalizer is selected and is effective to cause the selected totalizer to perform a non-add operation.

The raising of the link 483 causes a stud 490 in a rearwardly-extending arm 491 thereon (Figs. 4 and 16) to act on the usual symbol setting lever 492 and rock it clockwise.

This clockwise movement of lever 492 will, through the coupling lever 489 move the symbol type bar into position to print a non-add symbol in the manner fully explained in the patent to Peters, No. 1,386,021.

When the #1 totalizer is selected for operation the #2 and #3 totalizers will be non-added under control of the totalizer selecting mechanism.

In a non-add operation with the #1 totalizer selected, the rocking of the lever 492 is used to prevent an entry in the totalizer. When the lever 492 is rocked by the further raising of the link 483, the lever 492 will engage a stud 493 in one arm 494 of a two arm lever and rock the lever to move the other arm 495 rearwardly, as shown in dot and dash lines in Fig. 16, to place a stud 496 thereon in the path of the pawl 281 to prevent the pawl from engaging the stud 284 on the three-armed lever 272 and returning the lever near the beginning of the return stroke of the arm 282.

In this operation, the pawl 281 will shift the lever 272 and pitman 271 to disengage the #1 totalizer near the beginning of the machine operation but will be ineffective to shift the lever 272 and pitman 271 to cause the totalizer to be engaged during the return stroke of the arm 282 thereby leaving the totalizer disengaged from the racks during their return movement. The finger 286 (Fig. 4) as it operates the totalizer engaging cam 253 to engage the totalizer with the racks after they have made their return movement, will cause the pitman 271, which is coupled to the cam 253, and the three-armed lever 272 to be restored to their normal positions.

Since the #3 totalizer engaging means is operated by a pitman 306 connected to lever 272, the above disabling of the pawl 281 by the arm 495 will prevent the #3 totalizer from receiving an entry in a non-add operation with the #3 totalizer selected. As explained earlier, the selection of the #3 totalizer automatically non-adds the #1 and #2 totalizers.

When the #2 totalizer is selected for operation, the #1 and #3 totalizers are automatically non-added by the selecting means as has been explained earlier herein.

The additional upward movement of the link 483 causes its arm 491 to engage a bent over extension 495 at the rear end of the lever 355 and rock the lever counterclockwise (Fig. 8) to the same position it occupies when the selecting lever 350 is in its #1 or #3 position. As explained earlier herein, with lever 355 in this position, the stud 341 is moved out of the path of the notch 342 in the segment 336 and the #2 totalizer will not be engaged with the racks during their return movement.

Thus no matter which totalizer is selected for operation, the operation of the Non-add lever 481 will be effective to prevent entries from being made therein.

While the form of mechanism herein shown and described is admirably adapted to fulfill the objects primarily stated, it is to be understood that it is not intended to confine the invention to the one form or embodiment herein disclosed, for it is susceptible of embodiment in various forms.

What is claimed is:

1. In a machine of the class described, the combination of a plurality of differentially operable actuating racks, one for each of a plurality of denominational orders; means to control the differential operation of the racks in adding and subtracting operations; a first totalizer having a corresponding plurality of totalizer wheels; a totalizer supporting frame in which said first totalizer is mounted, said frame being shiftable to engage and disengage the wheels of the first totalizer with and from the racks of corresponding denominational orders; a second totalizer having a corresponding plurality of denominational totalizer wheels which are located within the supporting frame for the first totalizer and in tandem relation with totalizer wheels of corresponding denominations of the first totalizer; a totalizer supporting frame in which said second totalizer is mounted, said frame in which the second totalizer is mounted being shiftable to engage and disengage the wheels of the second totalizer with and from the racks of corresponding denominational orders; means selectively operable to shift the frames individually to engage and disengage one or the other of the totalizers with and from the racks in adding or subtracting operations; tens transfer control mechanism for controlling the racks to cause an entry of a value of "one" to be made in a higher order wheel of a totalizer each time the entry next lower order wheel exceeds its capacity, said tens transfer control mechanism being common to the two totalizers and including a transfer lever for each denominational order, each of which levers is common to the two totalizers and controls the rack of next higher order to make the tens transfer entry in that order, and also including a transfer cam secured to each of the totalizer wheels, which cams are operable to cause an operation of the transfer levers of their related denominations to cause the racks of the next higher orders to operate and enter "one" in the totalizer wheels of those orders of a totalizer whenever that totalizer has been engaged with the racks and the entries in the totalizer wheels of the next lower orders have exceeded their capacity.

2. In a calculating machine having a main operating means for giving the machine cycles of operation; two main totalizers; an extra totalizer; selectively operable digit-key mechanism; a differential actuator mechanism given permissible excursions of movement under digit-key 75

control in item-entering operations, and under totalizer control in total-taking or sub-total-taking operations; a totalizer selecting means adjustable to select any one of the three totalizers 5 for engagement with the differential actuator mechanism during ensuing machine operations; totalizer engaging mechanisms for the two main totalizers, which through the main operating means leaves the said two main totalizers in engagement with the differential actuator mechanism at the end of a machine operation, if not already in such engagement; a totalizer engaging actuator mechanism for each of said two main totalizers, each normally conditioned to disengage the associated totalizer from the differential actuator mechanism during the first half of a machine cycle and to engage such during the second half of a machine cycle, in item-entering timing, each said totalizer engaging actuator 15 mechanism being adjustable to cause the engagement of its associated totalizer in total-taking, sub-total-taking, or non-add timing; total-taking control means adjustable to cause the totalizer engaging actuator mechanism to cause the selected one of said two main totalizers to engage the differential actuator mechanism in total-taking timing or sub-total-taking timing; non-add control means adjustable to cause the totalizer engaging-actuating mechanism to cause the selected one of said two main totalizers to engage the differential actuator mechanism in non-add timing; the combination of totalizer engaging means operable to engage or disengage the extra totalizer from the differential actuator mechanism; means normally conditioned to act upon the extra totalizer engaging means to disengage the extra totalizer from the differential actuator mechanism at the beginning of a machine operation if not then disengaged, but disabled by the total-taking control means when it is adjusted for total-taking or sub-total-taking, and the totalizer selecting means is adjusted to select said extra totalizer for engagement with the differential actuator mechanism; and means adjusted by the totalizer selecting means when adjusted to select said extra totalizer for normally causing the main operating means to engage said extra totalizer with the differential actuator mechanism during the second half of a machine cycle.

3. The machine of claim 2, in which the totalizer selecting means, when adjusted to select the extra totalizer in conjunction with the adjustment of the total-taking control means to its total-taking or sub-total-taking condition, engages the extra totalizer with the differential actuator mechanism, if not already in such engagement, without the intervention of the main operating means.
